TIEBACK HOLDING HARDWARE FOR DRAPIERIES

John R. Hedger, 4958 E. Carmen, Fresno, Calif. 93727

Filed Jan. 27, 1975, Ser. No. 544,489

Term of patent 14 years

Int. Cl. D8—09

U.S. Cl. D8—214

FIG. 5

FIG. 1 is a side elevational view of tieback holding hardware for draperies;

FIG. 2 is a top plan view;

FIG. 3 is a side elevational view from 180° to the view of FIG. 1;

FIG. 4 is an end elevational view looking toward the right-hand end of FIG. 1; and

FIG. 5 is an end elevational view looking toward the left-hand end of FIG. 1.

I claim:

The ornamental design for tieback holding hardware for draperies, as shown.
